UNITED STATES PATENT OFFICE.

JOSEPH H. RUSBY, OF NUTLEY, NEW JERSEY.

ELECTRIC SWITCH.

SPECIFICATION forming part of Letters Patent No. 741,168, dated October 13, 1903.

Application filed March 20, 1902. Serial No. 99,177. (No model.)

To all whom it may concern:

Be it known that I, JOSEPH H. RUSBY, a citizen of the United States, residing at Nutley, in the county of Essex and State of New Jersey, have invented new and useful Improvements in Electric Switches, of which the following is a specification.

This invention relates to a switch which can be readily applied or adjusted in its required position and which can be made shallow or so as to occupy but little space.

The invention resides in the novel features of construction set forth in the following specification and claims and illustrated in the annexed drawings, in which—

Figure 1 is a side elevation of the switch sectioned along $x x$, Fig. 3. Fig. 2 is a section along $y y$, Fig. 3. Fig. 3 is a front elevation of the switch, the cover being removed. Fig. 4 is a section along $z z$, Fig. 3. Fig. 5 is an edge view of contact-making blades. Fig. 6 is a face view of Fig. 5. Fig. 7 is a plan of the lower face of the cover, and Fig. 8 an end view of Fig. 7.

In the drawings is shown a suitable support a , which may be an outlet box or wall or any suitable rest or supporting means. The switch or rather the switch frame or body b is made of suitable insulating material. Porcelain has been found satisfactory and can be given any desired shape. This switch b is shown adjustable both laterally and transversely—that is, adjustable either from side to side in the plane of the wall a or in and out of the wall. By having opposite portions or top and bottom ends of the box adjustable independently of one another the switch after it is applied to its support can be either set as required to be brought to exact vertical adjustment or set to be flush or parallel with the wall. A neat and finished appearance can thus be secured without it being necessary to exactly prepare or adjust a seat or the support a before the switch is put in place.

The adjustable connection between switch-frame b and support a is shown formed by movable or swinging lugs or connections c , having seats or forked ends for the engagement of screws d on support a and also tapped for the engagement of the threaded spindles or rotary screws e , carried by switch b and forming an adjustable connection between

the switch and the lugs. These rotary screws e are held against longitudinal movement in or relatively to switch b , and as these screws 55 or either of them is turned one way or another the switch is adjusted transversely—that is, into or out of support a . In other words, these spindles e might be called “leveling-screws.” Swinging one or both the lugs 60 c on pivots d to one side or another will secure lateral adjustment for the switch. By tightening the screws d the lugs c can be fixed against swing or accidental movement after having been adjusted. The screws e after having been adjusted can also be fixed or locked 65 against rotation, as presently explained.

A cover or top plate f is shown adapted to be secured to or carried by the switch b so as to be adjustable therewith—that is, when the 70 switch has been properly leveled and elevated or sunk the cover f carried by the switch will consequently be seated in proper position. The cover is adapted to be secured to the screws e , the latter being centrally tapped for 75 the engagement of the cover-securing screws g , so that the cover is connected to the switch or to the screws e , forming, as it were, part of the switch. Said cover when in place is also adapted to lock the screws e or prevent 80 rotation of the same, said cover having lugs or stops h , Fig. 3, projecting therefrom and engaging the heads or slots of screws e eccentrically or to one side of the central taps. When the cover f is thus secured to screws e 85 and the lugs h engage such screws, the latter are locked, and the adjustment of the switch is not liable to be accidentally disturbed.

The cover f has perforations for the exposure of the actuating-handle of the switch, 90 which handle can be either buttons or a lever-handle or both, as known in the trade.

It might be here noted that each rotary spindle e is held in switch b against longitudinal movement by suitable means, such as 95 the ordinary screw-head, which can be applied at one end of the spindle, and by a washer or spring and nut applied at the other end of the spindle or against the face of the porcelain opposite to that against which the screw-head sits when the screw is in its place and which nut can be suitably secured against withdrawal or loss—as, for example, by riveting or soldering.

The frame *b* supports or has connected thereto a bearing or plates *i*, supporting axles or rock-shafts *k* and *l*. The shaft *k* forms a carrier for the blades *m*. Two pairs of blades 5 are shown, but the description of one applies to the other. As the blade *m* snaps to and from the contact strip or post *q* the contact is made or broken. The blade *m* is shown forked or split, so that it will straddle a suitable projecting part or strip of post *q* or that such strip, as it were, cuts into blade *m* for close contact. The post *q* is shown with binding-screw *r*, and a shoulder or flange *q'* forms a stop on the post, so that in wiring the conductor or end of the wire cannot be slipped or push over or past the post so far as to contact with or permanently touch any undesired part of the device. Short or wrong circuits are thus avoided.

- 20 Of course it is understood in the art that the blades *m* are suitably insulated, as required. By having the shaft *k* provided with insulating-disks—as, for example, porcelain blocks *8*—to which the blades *m* are suitably 25 screwed or secured, such blades can be kept insulated. The edge of each block or disk *8* can be suitably beveled to allow the blades play or lateral bend or spread when crowded onto or straddling the tongue or post *q*. 30 These disks *8* can be only partly perforated, so that while shaft *k* can project part way into the disk the latter forms an insulating cap or cover for the respective end of the shaft. The shaft can have a cross head or 35 arms to which the disk can be secured by suitable screws *9*, Fig. 5, and the blades *m* can be suitably screwed or secured to the disks or across the outer faces thereof.

The shaft *k* is shown with a seat portion *k'*, 40 having a plunger *s* of concave or cam-face shape and whose stem *s'* is guided by the seat or tail *k'*. This tail *k'* also forms a stop, since by striking against one or another point of bearing *i* this tail limits the rocking of 45 shaft *h*, and the lever *3* can also act as a stop, since by striking against one or another of the lugs or projections *1*, Fig. 2, this lever limits the play of shaft *l* and the tail limits the oscillation of shaft *k* with plungers *s*. A spring 50 *t* tends to press this plunger *s* toward plunger *2*, seated in lever *3* on fulcrum *l*. The spring of plunger *2* is shown at *4*. The plunger *2* can be prevented from rotating by any suitable cross-pin or other suitable appliance or 55 by being made angular or non-circular while left free to move longitudinally.

Only one spring and plunger could be employed, but by having two the size and play of each spring can be diminished, which is 60 of advantage as facilitating the application of the device to a shallow or limited space, and besides the liability of breakage is diminished as the play of each spring is lessened.

65 As the lever *3* is moved to swing its plunger back and forth along track or plungers *s* to one side or another of center or shaft *k* this

shaft is rocked to snap the blades *m* into or out of circuit.

In case a lever-handle is employed the part 70 5 of this handle at the passage slot in plate *f* is formed as an arc about the center of oscillation *l*, so as to keep in close contact with and practically shut this slot. This handle-lever can be fixed to lever *3* or be connected 75 thereto by rack-and-pawl connection, such as is employed to place the projecting lever or handle part at different angles to lever *3*, so as to obtain adjustability.

In case buttons *6* are employed for actuating lever *3* the connecting-links *7* for these buttons are pivoted both to the levers and to the buttons or to plugs screwed or secured to the buttons, so that each double-pivoted link allows its button to have smooth play through 85 the respective perforation in plate *f*.

As the fulcrums *k l* can be placed parallel and near to one another and the plungers *s* and *2* can be made short, the switch can be made shallow, so as to require comparatively 90 little space for its seating or adjusting.

What I claim as new, and desire to secure by Letters Patent, is—

1. A switch and centrally-tapped adjusting-screws for the switch, combined with cover-attaching screws adapted to engage said taps, substantially as described. 95

2. A switch and supporting-lugs combined with rotary screws for adjustably connecting the lugs and switch, said screws being held 100 against longitudinal movement, substantially as described.

3. A switch comprising an actuating-lever, a blade-carrier, a shaft for the carrier, a plunger mounted in said shaft and engaging 105 with said lever and bearing-plates for said shaft and lever.

4. A switch comprising an actuating-lever and blade-carrier with spring-pressed plungers, one of the plungers having a face or 110 cam portion forming a way for the other plunger, substantially as described.

5. A switch comprising an actuating-lever provided with a plunger, and a blade-carrier having a spring-pressed cam engaged by said 115 plunger, substantially as described.

6. A switch comprising a blade-carrying shaft, a yielding or spring - actuated cam seated in said shaft, an actuating-lever for the cam, and bearing-plates for supporting 120 said lever and blade-carrying shaft, substantially as described.

7. A switch comprising a blade-carrying shaft provided with a seat portion having a nose or projection forming a stop, and a 125 yielding or movable cam mounted in the seat portion and having a stem guided by said nose, substantially as described.

8. In a switch a bearing, a lever fulcrumed therein, a blade-carrying shaft journaled in 130 said bearing below said lever, and a spring-actuated cam seated in said shaft and separate from and engaged and actuated by the said lever.

9. In a switch a binding-post provided with a tongue, a forked blade fitted to straddle said tongue, a rock-shaft carrying said blade, a spring-actuated cam seated in said rock-shaft, a bearing for said shaft, and a lever fulcrumed in said bearing independent of the said shaft.
10. A switch comprising a blade-carrying shaft, bearing-plates for said shaft, a lever fulcrumed in said plates independent of the shaft, a spring-actuated cam seated in said shaft, a spring-pressed plunger connected with the lever, operated thereby and adapted to engage with said cam for actuating it, links pivoted to the lever and buttons carried by said links.
11. A switch having supporting-lugs, adjusting-screws for the lugs, and a cover adapted to be secured to and to lock the screws against rotation, substantially as described.
12. A switch having supporting-lugs, centrally-tapped adjusting-screws for the lugs, cover-securing screws made to engage the taps, and a cover having lugs or stops made 25 to eccentrically engage the adjusting-screws for locking the latter, substantially as described.
13. In a switch a bearing, a lever fulcrumed therein, a blade-carrying shaft mounted in 30 said bearing independent of the lever, a cam seated in said shaft and engaged and actuated by the said lever, and a handle adjustably connected to said lever.

In testimony whereof I have hereunto set 35 my hand in the presence of two subscribing witnesses.

JOSEPH H. RUSBY.
